[57] CLAIM

The ornamental design for a portable blower, as shown and described.

DESCRIPTION

FIG. 1 is a perspective view of a portable blower, showing our new design;

FIG. 2 is a side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective view of the second embodiment thereof;

FIG. 8 is a side elevational view thereof;

FIG. 9 is a top plan view thereof;

FIG. 10 is a bottom plan view thereof;

FIG. 11 is a front elevational view thereof;

FIG. 12 is a rear elevational view thereof;

FIG. 13 is a partial rear elevational view thereof, with the guard removed;

FIG. 14 is a side elevational view of the third embodiment;

FIG. 15 is a partial side elevational view thereof;

FIG. 16 is a partial front elevational view thereof;

FIG. 17 is a partial side elevational view of the rear portion thereof; and

FIG. 18 is a partial rear elevational view thereof.

FIG. 1FIG. 2FIG. 3FIG. 4FIG. 5FIG. 6FIG. 7FIG. 8FIG. 9FIG. 10FIG. 11FIG. 12FIG. 13
